UNITED STATES PATENT OFFICE.

JOHN W. TOLLIVER, OF BUFFALO, NEW YORK.

ROTARY INTERNAL-COMBUSTION ENGINE.

1,296,880.

Specification of Letters Patent. Patented Mar. 11, 1919.

Application filed August 12, 1918. Serial No. 249,529.

To all whom it may concern:

Be it known that I, JOHN W. TOLLIVER, a citizen of the United States, residing at Buffalo, in the county of Erie and State of New York, have invented certain new and useful Improvements in Rotary Internal-Combustion Engines, of which the following is a specification.

The invention relates to rotary engines of the internal combustion variety and more particularly to engines of the two-cycle type, and has for its object to develop a maximum amount of power from a given quantity of fuel, and also to reduce vibration to the smallest amount possible, and to have the impulses in rapid succession.

The main object of the invention is to utilize a cylinder, and a coöperating piston as means for drawing a charge of fuel from a source of supply and compressing such charge preliminary to ignition, the expanding gases resulting from combustion being utilized to impart movement to a rotor from which the developing power is taken for operating the part to be driven.

A further purpose of the invention is the provision of an engine of the character aforesaid, embodying a plurality of cylinders and pistons, which are grouped about a central point and forming parts of the rotor, the cylinders being provided in number corresponding with the size and capacity of the engine, so as to obtain the required number of impulses during each complete revolution of the rotor.

A further purpose of the invention is the provision of an engine of the character hereinbefore specified, which involves a simple construction and relation of parts so that replacements and adjustments may be easily, quickly, and economically made without necessitating throwing the engine out of commission for any great period during which it is required to utilize the engine.

The drawing illustrates a preferred embodiment of the invention; however, it is to be understood that in adapting the same to meet different conditions, various changes in the form, proportion, and minor details of construction may be resorted to without departing from the nature of the invention as claimed hereinafter.

In the drawings:
Figure 1 is a central radial section of a

rotary internal combustion engine embodying the invention;

Fig. 2 is a central horizontal section thereof, showing the parts on a larger scale, the rotor being turned to bring opposite horizontal cylinders in the plane of the supporting frame;

Figs. 3 and 4 are enlarged sectional details on the lines 3-3 and 4-4 of Fig. 1 respectively.

Corresponding and like parts are referred to in the following description and indicated in both views of the drawings by like reference characters.

The engine comprises a stator and a rotor and is adapted to be mounted upon a suitable bed or foundation, not shown, by means of an oblong frame, which is provided at its ends with brackets 2. A shaft is disposed centrally of the stator or casing 1 and comprises the elements 3 and 4, and intermediate crank portion 5. This shaft is fixed. The portion 3 of the shaft is provided at one end with a flange 6, which is secured to a side of the frame 1. The element 4 receives a hollow shaft 7 which is secured at its inner end to the rotor and which is journaled in the opposite side of the frame 1. The hollow shaft 7 has a flange 8 at its outer end, and a flange 9 at its inner end. The flange 9 is secured to the rotor, thereby causing the hollow shaft 7 and rotor to rotate in unison. The outer end of the hollow shaft 7 is made tapering as indicated at 10 to receive a pulley (not shown) and which is adapted to be secured to the flange 8. The member secured to the projecting end of the hollow shaft 7 may be a fly wheel, a propeller, or other part depending upon the specific purpose to which the engine is applied.

The rotor comprises an inner casing 11, a plurality of cylinders 12 radiating from the outer wall of the casing 11, a hollow rim or outer casing 13 connecting the outer ends of the cylinders 12, abutments 14 slidably mounted in openings formed in the inner wall of the hollow rim 13, pistons 15 disposed within the cylinders 12, and rods 16 connecting the pistons 15 with the crank portion 5 of the crank shaft, the latter comprising the elements 3, 4, and 5.

Each of the cylinders 12 is provided near its outer end with a partition 17. The space

18 formed between the partition 17 and the part of the inner wall of the hollow rim 13 closing the outer end of the cylinder constitutes in effect, an explosion chamber, since 5 the mixture is ignited therein at the proper point in the rotation of the rotor. One or more outwardly opening valves 19 are disposed in the partition 17. Outwardly opening valves 20 are provided in the head of 10 each of the pistons 15. The valves 19 and 20 may be of any type commonly embodied in internal combustion engines. The abutments 14 are slidably mounted in the portions of the inner wall of the hollow rim 13 15 closing the outer ends of the cylinders 12, and each of the abutments 14 is provided with a passageway 21, whereby communication is had between the combustion chamber 18, and the space 22 inclosed by the hollow rim 13. As indicated most clearly in Fig. 20 1, the space 22 is uninterrupted for a little more than one-half the circumference of the hollow rim. The remaining portion of the space 22 is occupied by a wall 23 which 25 fits close against the outer face of the inner wall of the hollow rim 13. The wall 23 is spaced from the adjacent portion of the outer wall of the hollow rim 13, as indicated at 24 and, if desired, such space may be 30 utilized for circulating a cooling medium therethrough. The wall 23 may be braced at intervals as clearly indicated in Fig. 1. A fixed abutment 25 is located at one end of the wall 23, and the opposite end of the wall 23 inclines to form a cam portion 26 on which the sliding abutments 14 ride and are 35 pressed inward into the chambers 18.

The casing 11 constitutes a crank case for receiving the crank portion 5 of the crank shaft, as also the inner ends of the rods 16 which are mounted upon the crank portion 5 of the crank shaft. One wall of the crank case 11 is mounted upon an enlargement 27 of the end 3 of the crank shaft. The opposite wall of the casing 11 has the flange 9 of the shaft 7 secured thereto. The shaft 7 is formed with an enlarged portion 28 and ball bearings are interposed between the part 28 and the reinforced part of the frame 1, in which the hollow shaft 7 is journaled. The crank portion 5 of the crank shaft is offset from the center of the rotor and in consequence of such arrangement the pistons 15 have a reciprocatory movement imparted thereto during the rotation of the rotor as will be readily understood. The inner ends of the cylinders 12 open into the crank case 11, and one end of the crank shaft, as 3, likewise opens into the crank case 11 and its outer end is in communication with a pipe 29, which is connected in any manner to a side of the frame 1. The pipe 29 is adapted to supply a gaseous mixture to the crank case 11 from a suitable source of supply.

65 The stator comprises a ring 30 which is

secured at opposite points to the ends of the frame 1. The hollow rim 13 consists of two similar annular members which are flanged at their inner edges and bolted together, the outer edges of the annular members engaging opposite sides of the ring 30 which simply fitted between them, packing being interposed between the opposing faces of the parts to insure close fitting joints. The parts 23 and 25 are secured to the ring 30 75 and are relatively fixed. Each cylinder is provided with spark plugs 31 opposite the explosion chambers 18.

In the operation of the engine, it being assumed that the rotor is in motion, the pistons reciprocate in the cylinders 12. On the out stroke of the pistons, the valves 20 are closed and the pistons serve to draw the gaseous mixture into the crank case 11, and the inner ends of the cylinders 12. The gas 85 confined between the heads of the pistons and the partitions 17 is compressed and passes through the valve controlled openings in the partitions 17, into the chambers 18. As the cylinders successively approach 90 the fixed abutment 25 the gas is ignited and the expanding gases pass into the space 22, from the chamber 18, through the passage way 21, in the abutment 14, which moves outwardly into the space 22 the instant such 95 abutment 14 clears the abutment 25. It will be understood that the gases react on the abutments 14 and 25 and as the latter is fixed the abutment 14 is caused to travel in the space 22 away from the abutment 25, thereby imparting an impulse to the rotor. This 100 brings the next cylinder into position for the firing of the charge contained therein. Each cylinder receives a charge, and the latter is fired therein at each revolution of the rotor. 105

A portion of the central ring 30 is formed with a plurality of openings 32 which constitute outlets for the exhaust. Exterior to the part of the ring 30, having the openings 32, is disposed an inclosed conduit or passage way 33 which communicates with an exhaust pipe 34 by means of which the spent gases are conveyed to a suitable point of discharge. The inner wall of the central ring 30, near the exhaust passage 33 is 110 formed with a channel 35 through which the spent gases are permitted to have an initial discharge. When the cylinders reach the inclined portion 26 of the wall 23 the abutments 14 ride on the inclined or cam 115 portion 26 and are moved inward, and during the travel of the cylinders 12, opposite the wall 23, the abutments 14 are held inward by riding upon the wall 23, and during this time the pistons 15 move outward 120 and compress the gas contained in the outer portion of the cylinders and force such gas into the explosion chambers 18, preliminary to ignition. As the cylinders reach the point 125 opposite and beyond the fixed abutment 25, 130

the mixture in firing the chambers 18 is ignited. The point of explosion may be determined by a suitable timing mechanism (not shown) and which is common in the 5 operation of internal combustion engines.

The foregoing description and the drawings have reference to what may be considered the preferred, or approved, form of my invention. It is to be understood that I may 10 make such changes in construction and arrangement and combination of parts, materials, dimensions, et cetera, as may prove expedient and fall within the scope of the appended claims.

Having thus fully described my invention, what I claim as new and desire to secure by Letters Patent is:

1. A rotary internal combustion engine, comprising a stator, comprising a casing 20 having a way or space in the inner face of a portion of the encircling wall, and having a fixed abutment at one end of the way, and a cam at the opposite end of such way, said stator having a plurality of openings in the 25 outer wall inclosing said way and having a closed passage exterior to the wall having the openings for receiving the exhaust, a rotor within the stator, a cylinder carried by the rotor, and having a combustion 30 chamber in its outer end, a sliding abutment at the outer end of the cylinder and adapted to extend into the way in the outer wall of the stator, and a piston mounted in the cylinder.

2. A rotary internal combustion engine, comprising a crank shaft having an end portion made hollow and adapted to be connected with a source of fuel supply, a crank case inclosing the crank portion of the crank 40 shaft, and in communication with the end of the crank shaft having connection with the source of fuel supply, a cylinder connected with the crank case and having a combustion chamber in its outer end, a piston 45 within the cylinder, a rod connecting the piston with the crank portion of the crank shaft, a stator receiving the several

parts, and having a way formed in the inner portion of its encircling wall and a sliding abutment mounted in the outer end of 50 the cylinder, and adapted to project into the way of the stator.

3. A rotary internal combustion engine, comprising a stator, a rotor embodying a hollow rim having a way formed in a portion thereof, a fixed crank shaft, a crank case inclosing a portion of the crank shaft, cylinders radiating from the crank case and opening therein, the crank shaft having an end portion establishing means of communication between the crank case and the source of fuel supply, partitions near the outer ends of the cylinders forming combustion chambers, valves in said partitions, pistons in the cylinders, and having outwardly opening 65 valves, rods connecting the piston with the crank portion of the crank shaft, and sliding abutments at the outer ends of the cylinders, and adapted to travel in the way formed in the encircling hollow rim. 70

4. An internal combustion engine of the rotary type, comprising a stator having a way in the inner wall of a portion of its encircling part, said way having a fixed abutment at one end, and an outlet for the 75 exhaust at its opposite end, a fixed crank shaft, a crank case inclosing the crank portion of the crank shaft, and in communication with the source of fuel supply through an end portion of the crank shaft, cylinders 80 radiating from the crank case, valved partitions at the outer ends of the cylinders forming combustion chambers, pistons in the cylinders, rods connecting the pistons with the crank portion of the crank shaft, and 85 sliding abutments in the outer ends of the cylinders.

In testimony whereof I affix my signature in presence of two witnesses.
